UNITED STATES PATENT OFFICE.

FOSTER J. HULL, OF HAGERSTOWN, MARYLAND, ASSIGNOR TO PANGBORN CORPORATION, OF HAGERSTOWN, MARYLAND, A CORPORATION OF MARYLAND.

SAND-BLAST BARREL AND ELEVATOR DRIVE.

Application filed February 17, 1926. Serial No. 88,820.

The invention relates to sand blast machines more particularly of the direct pressure type in which castings or other articles to be subjected to the abrasive action are placed in the barrel or cylinder of the machine, the blast of air and abrasive particles being introduced near the centres of the axial ends of the barrel which is rotated to agitate the castings and expose their various faces in turn at the surface of the load where they encounter the abrasive stream. While the term "sand blast" is used for convenience, other abrasives than sand are generally used.

The castings fill the barrel a little less than half full, so that more than half the area of the cylindrical wall is uncovered. This wall is perforated and the abrasive together with the dust and the dirt removed from the castings is dropped through the perforations into a convenient enclosure at the bottom of the machine, whence it is removed by suitable means shown in the form of an elevator or conveyor chain.

The abrasive is then cleaned, sifted and returned by way of the blast. The cleaning of the abrasive, etc., however, forms no part of the present invention. In the form shown the barrel is enclosed within a casing from which the air is exhausted to keep down the dust.

In order to prevent undue accumulation of the abrasive, dirt and dust in the area at the bottom of the machine, and to dispose of any quantity which may accumulate during the operation of the machine, the conveyor or elevator runs continuously, the barrel being started and stopped at the will of the operator to provide for loading and dumping of the barrel and inspection of the parts.

The invention relates to means for rotatably supporting, guiding and driving the barrel, and to conjointly driving the barrel and conveyor or elevator, providing for stopping and starting the barrel while the conveyor runs continuously.

To avoid the expense incident to producing and maintaining closely fitted ground bearings to support the weight of the barrel, it is provided with hard metal peripheral bands or tires which engage hard metal rollers by which the drum is supported and driven. On account of the large diameter of the drum, the present common size of drum being fifty inches inside diameter, turning and grinding of these tires would be exceedingly expensive, and to avoid this expense, they are preferably

made of hard rolled steel or correspondingly hard metal, the rolled face of the tire engaging and bearing on the rollers.

The supporting rollers comprise in the preferred form of machine shown idler rollers which may be set a little forward of the centre of the drum and driving rollers more nearly at the centre of the drum receiving a larger proportion of the weight, thereby increasing the friction and contributing to a more positive drive.

Rotary drums, etc. are in some instances guided to prevent lateral play and side creep by means of flanges, but in cleaning castings by the present method, the weight of the drum and load is so great that flanges are not effective and are soon ground away.

To take up and limit the side play and to take up end thrust or side thrust, side thrust rollers are provided which engage surfaces on the drum transverse to the axis of rotation. In the present instance the side thrust rollers engage the edges of the bands or tires.

These side thrust rollers as shown are tied to the frame by a tension member which applies the side thrust directly to the frame. The tension member is preferably adjustable and the rollers are so adjusted as to allow a slight degree of side play, one quarter of an inch being a convenient adjustment.

The driving mechanism in this type of machine has in the past given a considerable amount of trouble on account of slippage of belts, wearing of pulleys and general deterioration on account of grit, requiring a large amount of attention to keep the machines running and involving loss of time for replacement of parts and adjustment.

The present structure comprises a positive all-metal, i. e., gear or gear and chain drive, from the motor or other source of power to the barrel or rollers and conveyor belt, the same being of such a nature that all the parts may be and are completely enclosed, to prevent the access of grit to the working parts. By means of the positive drive, dispensing with belts and other devices of uncertain operation, practically all delays incident to the necessity for replacing belts which have run off the pulleys, renewing and tightening belts, etc. are eliminated and avoided, the conveyor or elevator being run continuously and the barrel being instantaneously stopped and started at the will of the operator. The control is carried to a point convenient for the

operator in filling, dumping, inspecting and otherwise attending to the operation of the machine, so that one operator can in fact control or operate efficiently a machine or several machines.

In the accompanying drawing I have illustrated a sand blast barrel and elevator drive embodying the features of my invention in the preferred form.

10 In the drawing—

Figure 1 is a rear elevation of the machine showing the location and general arrangement of the drive and elevator, the parts being enclosed.

15 Figure 2 is a fragmentary side view looking from the left in Figure 1, showing the motor and adjacent parts of the drive.

20 Figure 3 is a detailed view of the gearing at the lower left in Figure 1 adjacent the motor, the casing being removed and the parts being shown in section on the line 3—3 Figure 2 and broken away above and at the right for convenience of illustration.

25 Figure 4 is a section on the line 4—4 Figure 1 looking to the right in that figure.

Figure 5 is an enlarged section on the line 5—5 Figure 4 showing the mounting of the front rollers and side thrust rollers.

30 Figure 6 is a view in the nature of a front elevation, the parts being broken away at the right to show a section on the line 5—5 of Figure 4 and on the left showing a section on the line 6—6 Figure 4.

35 Figure 7 is a view on the line 7—7 Figure 1 showing the gearing and pulley at the upper end of the elevator drive shaft.

40 Figure 8 is a detail of a side thrust roller unit, the same being in the nature of a central section on the axis of the roller.

45 Figure 9 is a sectional view of an alternative belt drive structure corresponding to Figure 3 and in the same plane.

Figure 10 is a side elevation looking from the operator's left which is the right in Figure 1.

Figure 11 is a section on line 11—11 of Figure 3.

50 Referring to the drawings by numerals, each of which is used to indicate the same or similar parts in the different Figures, the machine as shown comprises a rotary sand blast barrel 1 enclosed within an outer casing 2, the illustration also including the elevator or conveyor 3, the barrel and elevator being driven by an electric motor 4 or from some other convenient source of power through an all metal drive 6 which is connected to the elevator for continuous operation of the latter and connected by way of the clutch 8 to the barrel drive rollers 9 providing for the rotation of the barrel at the will of the operator.

55 To the end that the barrel and the elevator may be driven from and by the electric motor 4 or from any suitable source of power as outlined, the motor shaft 11 is connected to a

bevel pinion 12, which meshes with bevel gear 14, which as shown is in the form of a toothed ring mounted on the flange 15, which is integral with sleeve 16 and spur gear 17, the exact construction and arrangement of such parts as described herein being more or less in the nature of details which may be widely varied within the scope of the invention. As illustrated, the sleeve 16, pinion 17 and bevel gear 14 are mounted to rotate on stud 7 which is secured to and in the casing 115 to be described.

60 In accordance with the preferred arrangement the bevelled pinion 12 is mounted on a separate shaft referred to herein as the pinion shaft 18 which for convenience in removing, for examination, adjustment and repairs, is mounted in a cage 19, the cage 19 with the shaft 18 and pinion 12 and roller bearings 20 for the shaft being assembled as a single unit. 70 The cage 19 is carried in the tubular support 21, which is secured to the frame being conveniently formed as part of casing 115. The shafts 11 and 18 are connected by a coupling 22 which is preferably a flexible coupling of 80 any well known type which provides not only for flexibility, avoiding the necessity for exact alignment of the parts, but for convenient removal of the shaft 18 and the pinion 12 in 85 and with the cage 19 as aforesaid.

90 The bevel ring or gear 14 driven by the pinion 12 as aforesaid carries a small spur pinion 17 on the sleeve 16 meshing with and driving the large spur gear 24 which is secured to the clutch sleeve 25 which is mounted in bearings 135, in casing 115, and rotates on and relatively to the horizontal shaft 26 extending across the back of the machine. This clutch sleeve 25 carries secured to its outer or left hand end as seen in Figure 3, a 95 bevel gear 27 which meshes with a bevel pinion 28 which drives the elevator shaft 29 through and by way of universal joint 30, the pinion 28 being mounted on a short shaft 32 which has a bearing 136 in the casing 115 and is connected by universal joint 30 to the elevator shaft 29. The universal joint 30 is provided at its upper side with a square socket 33 which is elongated in the direction of the length of the shaft, and shaft 29 has a square 100 elongated end 34 which has a sliding fit in said socket providing a driving connection with end play in the direction of the length of the shaft. The shaft 29 is connected at its upper end, see Figure 7, through a second universal joint 36 to a short shaft 37 mounted in tubular extension 127 of casing 128 and has secured thereto a bevel pinion 38 which meshes with and drives a bevel gear 39 on 105 and secured to a short horizontal shaft 40 mounted in suitable bearings 41 in the casing. This shaft carries at its inner end secured thereto a pulley 42 which drives the elevator 3, which, as shown, is in the nature of a conveyor belt 43 having small buckets or pockets 44 se-

110

115

120

125

130

cured to its outer surface. This belt runs over an idler pulley 45 at the lower end of the belt traverse, and the buckets 44 pick up the used abrasive with the dirt from the castings 5 and whatever dust it may carry, i. e., whatever dust has not been carried off by the exhaust, the abrasive, dirt, etc. being delivered to the bottom of the elevator casing 46 by way of a downwardly inclined chute or passage 47 10 leading from beneath the barrel. The barrel is perforated as to its entire cylindrical area, and the abrasive is discharged through the perforations and dropped into chute 47. This chute is provided at its upper end with 15 a deflector or shield 35 which catches some of the material thrown off from the barrel and deflects it toward the chute. The shields arrest the outward motion of the particles and direct them into the chute. The universal 20 joint and the slip joint prevent binding of the gears, etc. in case of vibration and relative motion of the different parts of the machine, which in such a structure cannot be avoided without unduly expensive rigid construction.

It will be apparent from examination of the drive so far as described, that the elevator or conveyor runs continuously as long as the motor is in operation or any other source of 30 power which may be used is connected to the drive. This provides for the removal of accumulations of abrasive, dirt and dust at the bottom of the machine, and tends to prevent accumulation which might interfere with the 35 efficient operation of the machine. The shaft 26 which through a series of connections to be described drives the barrel, is operated intermittently at the will of the operator, being connected to and disconnected from the continuously running sleeve 25 carrying bevel gear 27 and spur gear 24 by means of the clutch 8 which comprises the continuously running sleeve 25 rotating on and relatively to the shaft 26, and a sliding clutch member 40 45 50 keyed to the shaft by any preferred type of key or feather 51, so that it rotates with and slides relatively to the shaft. The sliding clutch member 50 and the continuously rotating sleeve 25 are provided with positively engaging clutch jaws 52 on their adjacent ends, and the sliding member 50 is moved and controlled by a forked clutch operating lever 54 which engages a groove 55 55 60 in the sliding member and is controlled by connecting rod 59, the same being universally connected at 58 to the depending arm 57. Rod 59 extends across the rear of the machine from the clutch to the right, as seen from the rear in Figure 1, and is connected to an eccentric pin 60 at the end of the rod remote from the clutch. The drawings show the parts in engaged position. The eccentric pin 60 is mounted in a rotating head 61 which is in turn mounted in suitable bearings 62 carried 65 in a bracket 63 on the machine frame.

The head 61 is secured to the rear end of actuating shaft 64 which extends from the rear to the front of the machine on the left of the operator and on the right as seen from the rear in Figure 1. This shaft 64 is supported by the head 61 in the bearing 62 at the rear and in a suitable bearing 65 at the front, and it is actuated by means of a hand crank 66 which is conveniently placed at the left of the operator as he stands in front of the machine, the clutch being engaged and disengaged, starting and stopping the rotation of the barrel as hereinafter described, by turning the crank backwards or forwards through a half turn.

The clutch 8 is illustrated in detail in the cross section, Figure 11, taken on the line 11-11 of Figure 3. The illustration shows the casing 127 provided with vertically arranged clutch shaft bearing 801, in which is mounted the clutch actuating shaft 802. The clutch actuating shaft 802 projects upwardly and downwardly from the bearing 801 and carries at its lower end outside the casing a rearwardly projecting horizontal arm 57, the 80 swinging end of the arm being forked at 581 and having mounted in the fork a vertical pin or block 803, which rotates about a vertical axis in the forked end of the arm 57. This pin is in turn straddled by the jaws 804 at the end of the rod 59 and a pin 58 is passed through the jaws 804 and pin or block 803 forming a vertically and horizontally swinging connection between the end of the arm 57 and the connecting rod 59.

The clutch actuating shaft 802 carries at its upper end, inside the casing 127, secured to the shaft as is the arm 57, a clutch operating fork 805, the arms or tines of the fork being indicated by reference characters 54. 105 This fork straddles or encloses the sliding clutch member 50 and each of the arms 54 carries a follower 806 which rides in the groove 55 of the sliding clutch member. Each of the followers 806 is connected to the corresponding arm 54 by means of an inwardly projecting radial pin 808, each said pin forming an inward projection or extension of a cap screw 809 seated in the corresponding arm. It is apparent that the clutch is connected when the rod 59 is thrust to the left in Figure 3 and disconnected when it is withdrawn to the right, the clutch member moving in the same direction as does the swinging end of the arm 57 and hence in the 110 same direction as the motion of the connecting rod 59.

Referring again to Figures 1, 3 and 4, the shaft 26 which is connected and disconnected, being thrown into and out of operation 125 by the clutch mechanism just described, is connected to the barrel to drive the same by means of chain and sprocket gearing 67 which operates the driving roller 9. The chain and sprocket gearing 67 comprises a 130

small sprocket 69 secured to the shaft 26 on the end thereof at the right of the observer in Figure 1. This sprocket meshes with and drives a chain 70 which in turn has a driving engagement with the large sprocket 71 on the end of the shaft 73 of the drive rollers 9 to which the rollers are secured.

Having particular reference to Figure 6, the barrel 1 is provided at each end with an outside circular track or band 75 which is preferably of hard rolled steel, the outer hardened rolled surface of each band bearing on the rollers. This obviates the necessity for grinding the tracks and rollers which would be exceedingly expensive, particularly in view of the large diameter of the barrel averaging almost five feet. This arrangement provides a low cost, accurate, dependable drive of long life and requiring little or no attention.

A frictional engagement of the tracks with the rollers sufficient to prevent slippage, is produced by the location of the rollers 9 beneath the barrel so that they support a considerable portion of the weight of the barrel, the driving rollers which are preferably at the rear being much nearer the centre and taking a much greater proportion of the weight than do the idler rollers 76 at the front. The driving roller shaft 73 is mounted in suitable bearings 77 in the machine frame one at each side, there being a driving roller 9 at each side of the machine at the rear to co-operate with each of the tracks 75 and an idler roller 76 at the front on each side to support the barrel at the front, one idler roller also engaging each track.

The driving rollers 9 are secured to the shaft 73 to rotate therewith. In the form of machine shown they are connected to the shaft by keys 78 and there is, as shown, a ball thrust bearing 79 between each roller 9 and the shaft bearing 77. The thrust bearings being inside the casing are protected from grit and dirt by means of cups 80 which enclose the thrust bearings and the ends of the bearings 77, the contact being sealed by means of soft packing rings 81 secured to the edges of the cups.

The means for restraining and limiting side creep of the drum or barrel is an important feature of the invention. The provision of flanges for this purpose would be the most usual and ordinary expedient, but with the great weight carried by the drum, flanges are not effective and are quickly cut and ground away. In the present instance side creep and play of the drum is limited, determined and adjusted within the desired limits by means of side thrust rollers 101 bearing on surfaces of the drum transverse to the axis. Preferably the rollers turn on axes disposed radially of the drum and bear on the edges of tires, bands or tracks 75. The side creep rollers or thrust rollers are placed at the front of the machine

for convenience of design and arrangement and so that they may be adjacent the front door opening where they are easily inspected, adjusted, and if necessary, removed and replaced.

70

The front rollers 76 in the form of the invention shown, are mounted to rotate freely on and relatively to a stationary transverse shaft 83 which extends across the machine from side to side, being supported at the sides 75 in adjustable brackets 84. All the rollers are of hard manganese steel although they may be of any suitable material. The roller 76 has a hard outer shell 85 of manganese steel and an inner bearing member 86 of softer material 80 which bears directly on the shaft, and it is placed between thrust bearings 87 which bear against laterally adjustable abutments 88 and 89 at each side of the rollers, said abutments being mounted to slide on the shaft 83. The 85 abutments 88 and 89 are apertured at 90 to admit the shaft and are adjusted laterally by means of tension rod 91, which is threaded for a considerable length at both end portions. The outer ends of the rod 91 are adjustably 90 held by nuts 92, one of which may be a lock nut in the brackets 84, which brackets are secured to the side frame members 170 by bolts 180. The rod passes through the brackets, the nuts being on the outer sides of the brackets, and the 95 abutments 88 and 89, and the rollers 76 between them, are positioned by means of nuts 93 and 94 engaging the tension rod 91 on each side of the depending extremities 95 of said abutments through which depending extremities the tension rod 91 is passed. The front supporting rollers 76 are preferably provided at each end with projecting cups 97 co-axially placed in respect to the rollers and having their rims projecting outwardly at each 100 side and taking over the bearings and complementary projections 98 of the respective abutments 88 and 89, so that they protect the thrust bearings 87 between said members 98 and 97 from grit and dirt as previously described in 110 connection with the driving rollers. Each of the cups is provided with an inwardly projecting soft packing ring 99 which bears against the complementary projecting member 98 providing a seal to protect the bearing. The 115 support 88 on the right is also provided with a shield 100 which projects over the cup for purposes of protection. The front rollers are thus adapted for adjustment to alignment with the tires or tracks 75 without danger of 120 cramping between abutments 88 and 89.

The side thrust rollers 101 are in the preferred form shown mounted on the outside abutments 89 of the front rollers. These abutments 89 are provided for this purpose 125 with upwardly projecting arms 102 which as shown, are at their upper ends turned inwardly over the thrust bearings 87 providing a support adjacent side edges 103 of the tires or bands 75 for the side thrust rollers 101. 130

In the preferred form each of the side thrust rollers is as already outlined, mounted on a pin 104 which is in turn adapted to be removably mounted in the arm 102 which is bored or 5 apertured at 105 to receive the end of the pin at the side of the roller providing a loose fit for the pin so that the pin and roller can be instantaneously mounted by hand without tools, or removed. The bore 105 is preferably 10 aligned with the radius of the drum so that the side thrust roller runs freely without slipping or binding on the side edge 103 of the tire or band or track 75 which may be termed an axial end surface of the ring or a surface 15 transverse to the axis of the barrel.

Each side thrust roller 101 forms with its pin 104, a unitary assemblage which as aforesaid, is placed in operative position and removed by inserting the pin 104 in the opening 20 or bore 105 in the support 102 and removing it. The roller unit as shown, Figure 8, and in the preferred form, comprises an outer cylindrical shell 107 which may be of manganese steel or other suitable hard material. 25 This shell 107 is in the form of the invention shown, mounted by means of roller bearings 108 on the pin 104 which is reduced at 109 forming shoulder 110 to receive the bearing members which are held between shoulder 30 110 and a nut 111 on the end of the pin. The bearings are positioned in the rollers by ring 113 which may be forced into shell 107. The roller is further shown as provided with a packing 112 adjacent the thrust end of the 35 pin to prevent the entrance of grit and the aperture within the roller is closed by a cap 114. The bearing is packed with grease.

Figure 5 shows the means for adjusting the front rollers 76 and more particularly 40 the side rollers 101 by means of the stress transmitting member 91 which is more specifically a tension rod and the nuts 92, 93 and 94. The preferred adjustment which is found most effective in practice allows a 45 slight degree of play between the tires or bands 75 and the side thrust rollers, the rollers being spaced about $\frac{1}{4}$ " further than the space between the outer edges of the bands or tires. The important advantage of this 50 feature of the invention is that the entire side thrust of the drum which when it is loaded, is very heavy weighing several tons, is entirely taken up by the anti-friction rollers referred to and transmitted directly to the frame applying the stresses due to side play where 55 they can be best taken up and resisted, and relieving all tendency to wearing and grinding of the parts on this account. The rollers 76 are adjustable as to alignment together 60 with the shaft 83 by moving the brackets 84 to the front or rear, the brackets being secured by bolts 108 in suitable slots. The shaft 83 is stationary and is held in position in the brackets 84 by set screws 109.

65 A feature of further interest in connection

with the all metal drive, is the fact that it is completely enclosed as to all its parts, preventing access of grit and dirt to the working parts and bearing surfaces and providing permanent lubrication, the casing being filled 70 with suitable lubricant which lasts almost the life of the machine.

The motor 4 which is any suitable type of commercial motor, is enclosed. The driving shaft 18 with its bearings etc. is a removable 75 unit as described, so enclosed as to prevent the access of grit. The bevel pinion 12, the bevel gear 14, the spur pinion 17 and the spur gear 24, and bevel gears 27 and 28 are enclosed within a casing 115 which is secured to 80 the frame of the machine and serves as a bracket and support for the bearings of the shafts and gears enclosed, the sleeve 21 which encloses the shaft unit 18 being integral with this casing.

85 The universal joint 30 is enclosed within a spherical casing 116 which cooperates with a cup 117 secured to the casing 115, the casing 116 being held in contact with the cup by means of a yoke 118 secured to the casing by 90 elongated bolts 119, the bolts being adjusted to a sufficient degree of tension to hold the parts in contact without causing them to bind.

95 The spherical casing 116 of the universal joint is provided with a tubular extension 120 which receives and encloses with a sliding fit, the end of tubular housing 121, which encloses the shaft 29, the tubular housing 121 being free to slide in and out of the member 100 120. The tubular housing 121 enters with a sliding fit within a corresponding tubular extension 122 of spherical casing 123 enclosing the universal joint 36, which is held by means of a yoke 124 and bolts 125 in running contact with cup 126, formed on the tubular extension 127 of the housing 128 which encloses and supports bevel gears 38 and 39 which operate the pulley 42 which drives the 105 elevator conveyor 3.

110 The clutch member 50 on the shaft 26 is enclosed within a casing 129 which is secured to the casing 115 and is provided with soft bushing or packing 130 surrounding the shaft 26 where it extends thru the housing. The shaft 26 is further provided at its other end with a collar 131 to take up end play where it enters the bearing 132 at the other side of the machine. There is also a shield 133 which projects over the collar and protects the bearing from grit. The sprockets and chains 69, 70 and 71 are enclosed within a casing 134 which is secured to the bearing 132 and suitably packed. The manner of protecting the driving roller and supporting roller bearings has been described. The housings are filled with grease which tends to prevent the entrance of grit and provides permanent lubrication.

120 In Figure 9 a belt drive capable of use al. 130

ternatively with the motor drive is illustrated. This includes a belt driven pulley 140 secured to a sleeve 141 which rotates freely on the shaft 142 corresponding to the shaft 26. This sleeve 141 carries secured thereto, a bevel gear 143 which drives a bevel pinion 144 corresponding to the pinion 28 in Figure 3, and connected by means of universal joint 30 to a shaft 29 which drives the elevator mechanism as in the previous instance. The sleeve 141 and the bevel gears 143, 144 and the shaft 29 run continuously giving a continuous operation of the elevator, the sleeve 141 is intermittently connected to the shaft 142, which corresponds to shaft 26, by means of a clutch 145 operated by connecting rod 59 and lever 57, Figure 11, as in the previous instance. Shaft 142 carries sprocket 69 and drives the barrel through rollers 9 as in the motor drive.

The belt driven pulley 140, Fig. 9, runs continuously so long as the machine is in use. The operation of the conveyor whereby the used abrasive combined with dirt from the castings and dust produced in the cleaning operation are removed from the base of the machine, is likewise continuous, the barrel being started and stopped for dumping and filling at the will of the operator. While the operation of the machine will be clear from the description it will be briefly outlined. In order that the barrel or drum may be stopped and started at the will of the operator to provide for filling and dumping the castings or other articles being treated, it is operatively connected with and disconnected from the continuously rotating sleeve 25 by means of the clutch member 50, the shaft 26 which is thus rotated intermittently being in turn connected by a continuous drive to the drum. The clutch is controlled through and by way of connecting rod 59 which is reciprocated in the direction of its length by eccentric pin 60 on the head 61, which is in turn mounted on actuating shaft 64 rocked by the crank 66 at the left of the operator, who stands at the front of the machine.

The continuous positive drive as described, to the elevator and driving rollers, not only provides for continuous operation of the elevator and intermittent operation of the drum as described, but gives the maximum of economy and efficiency by dispensing with the slippage and loss incident to belt driving and with the expense for attention incident to the operation of such mechanism.

The driving mechanism described with the universal joints at both ends of the elevator driving shaft 29, also including the slip joint 34 at one end, dispenses with the necessity for careful alignment and absolutely rigid construction, vibration and swaying of the structure do not cause binding or cramping of the drive.

The all metal drive is also practically in-

destructible under ordinary running conditions, and of a normal length of life which is so nearly unlimited that deterioration of this part of the machine is not an element of the expense in operation, and loss of time of the machine on account of failure of the drive is practically eliminated. An important contribution to this end results from the provision of the gear casings serving as an efficient grease retaining means and the complete protection of the working parts from grit and dust, the presence of which in large quantities during the operation of machinery of this general type having been one of the conditions which has heretofore prevented the development of the gear drive in this connection.

The manner of mounting, supporting and driving the drum on idler rollers 76 and driving rollers 9, and taking up side thrust by means of side thrust rollers 101, are together and separately regarded as important features of the invention.

The use of bands or tires 75, preferably of rolled steel, for engagement with the rollers, the hard rolled surface of the bands being turned outwardly for contact with the rollers, these parts being necessarily exposed to the grit and dust, gives with the use of hard metal rollers and bands a driving and supporting arrangement which is of long life, easily replaced and capable of production at a comparatively small cost. Also the necessity for the comparatively expensive operation of turning and grinding the bands, which on account of the large diameter of the drum is normally about 50 inches, would be a very considerable item, is obviated.

The side thrust rollers bear on the edges of the tires or bands, or any convenient surfaces of the drum transverse to the axis. This feature and the construction whereby the side thrust rollers are tied to the frame by tension rods applying the side thrust directly to the frame and providing for convenient adjustment as to the side play, and the manner of mounting the side thrust rollers whereby they are not only conveniently accessible, but capable of instantaneous removal and replacement preferably of the entire unit, are also regarded as improvements of great importance.

I have thus described specifically and in detail a sand blast barrel and elevator drive and barrel mounting embodying the features of my invention in the preferred form in order that the nature and operation of the same may be clearly understood; however, the specific terms herein are used descriptively rather than in a limiting sense, the scope of the invention being defined in the claims.

What I claim and desire to secure by Letters Patent is:

1. In a sand blast machine, a rotary barrel, a rotary member engaging a confronting,

- transverse surface of the barrel and restraining end play of the barrel, a shaft parallel to the axis of said barrel, a support for said rotary member slideable on said shaft, and means 65
 5 for adjusting said support and rotary member along said shaft to determine the end play of the barrel.
2. In a sand blast machine having a rotary barrel, a frame, a member engaging a 10
 10 fronting, transverse surface of the barrel, stress transmitting means connecting the engaging member to the frame, taking up the end thrust of the barrel and transmitting it to the frame, said member being adjustable 15 longitudinally of said stress transmitting means.
3. A sand blast machine having a frame, a rotary barrel, a rotary member engaging the barrel in a plane transverse to the axis of 20
 20 rotation of the barrel and taking up side thrust, means on the frame on which said rotary member is slidably supported, and a tension member connected to said rotary member and to said frame whereby the side thrust 25 of the barrel is transmitted to the frame, and means for adjusting the length of the portion 90 of the tension member between the rotary member and the frame.
4. A sand blast machine having a frame, a 30
 30 rotary barrel, an anti-friction member engaging the barrel in a plane transverse to the axis of rotation of the barrel and taking up the side play, means on the frame supporting said anti-friction member, and stress transmitting 35
 35 means connected to said anti-friction member and to said frame whereby the side thrust of the barrel is transmitted to said frame means for adjusting said anti-friction member longitudinally of said stress transmitting means, 40 and means for adjusting said stress transmitting means.
5. In a sand blast barrel machine, a frame, a rotary barrel, an anti-friction member mounted on the frame to move in the direction of the axis of the barrel, and engaging a 45
 45 surface of the barrel transverse to the axis of rotation, a tension member connected to the frame and to the anti-friction member, the latter member resisting the side thrust of the barrel and transmitting it to the frame through the tension member, and means for 50
 50 adjusting the tension member to determine the side play of the barrel.
6. In a sand blast machine, a rotary barrel, 55
 55 rollers supporting the barrel, a side thrust roller engaging a surface on the barrel transverse to the axis of the barrel, a support for the roller movably mounted relative to the frame of the machine providing for motion 60
 60 of the side thrust roller in the direction of the axis of the barrel, a screw threaded stress transmitting member engaging the roller support and connected to the frame of the machine, and a nut for adjustably positioning
- said stress transmitting member thereby moving the support in the direction of the axis of the barrel to regulate the side play of the barrel. 65
7. The combination with a sand blast barrel machine of a barrel member and a side thrust roller the barrel having a surface transversely to the axis, engaged by the roller, a pin on which the roller is mounted for rotation, the sand blast barrel machine having on its frame a carriage with a socket to receive the pin to hold the roller in operative position in engagement with the barrel and means for adjusting the carriage in a direction substantially parallel to the axis of the barrel. 70
 75
8. In a sand blast barrel machine, a rotary barrel, a side frame adjacent each end of the barrel, supporting rollers on which the barrel is mounted for rotation, a shaft on which the supporting rollers are mounted, side thrust rollers engaging opposite surfaces of the barrel transverse to the axis of rotation, carriages for the side thrust rollers slidably mounted, a tension means connected to both the side frames and to both the side thrust 90
 90 roller carriages for transmitting the side thrust of the barrel to the frame, and means for adjusting the tension means, thereby moving said carriages to determine the side play of the barrel. 95
9. In a sand blast barrel machine, a rotary barrel supporting rollers on which the barrel is mounted for rotation, a shaft on which the supporting rollers are mounted, side thrust rollers engaging surfaces of the barrel transverse to the axis of rotation, carriages for the side thrust rollers slidably mounted on said shaft, a stress transmitting member connected to the frame and to the side thrust roller carriages, means for adjusting said carriages longitudinally of said stress transmitting member, moving said carriages along the shaft to determine the side play of the barrel and to transmit the side thrust of the barrel to the frame, said carriages bearing on the 100
 100 ends of the supporting rollers and thrust bearings between the carriages and supporting rollers whereby the supporting rollers are positioned by and with the side thrust rollers. 110
10. In a sand blast barrel machine, a rotary barrel having peripheral tires, rollers engaging the tires providing a rotary support for the barrel and side thrust rollers engaging the edges of the tires in a plane transverse to the axis of the barrel to take up the end play of the barrel and keep the tires in contact with the rollers, a shaft on which the supporting rollers are mounted, carriages for the side thrust rollers slidably mounted on said shaft, and stress transmitting means connected to the frame of the machine and to said carriages, and means for adjusting said carriages longitudinally of said stress transmitting means. 115
 120
 125

ting means to position the side thrust rollers to limit and determine the side play of the barrel.

11. In a sand blast machine having a rotary barrel, an elevator for removing the abrasive and dirt discharged from the barrel, a source of power and positive connections from the same to the elevator and to said barrel, the connections to the elevator including a pair of universal joints and a shaft floating therebetween, the connections to the barrel including a clutch with clutch operating means within the control of the operator and rollers supporting the barrel for rotation and for driving it.

12. In a sand blast machine having a rotary barrel, means for removing the discharged abrasive, a source of power, a drive from said source of power to said means, and to the barrel for rotating the barrel, the driving connections to the abrasive removing means including a shaft, a universal joint and a slip joint providing for lateral and end play of the shaft due to vibration and swaying of the parts of the machine.

13. In a sand blast machine, a rotary barrel, means for removing abrasive discharged from the barrel, a motor, driving connections from said motor to said abrasive removing means comprising toothed gearing, a shaft, universal joints and a slip joint, connections from part of said toothed gearing to the sand blast barrel to drive the same, said latter connections including a clutch and means within the control of the operator for operating said clutch to start and stop the barrel independently of the conveyor.

14. In a sand blast machine having a rotary barrel, rollers on which the barrel is mounted

for rotation, a shaft for said rollers, side thrust rollers bearing on surfaces of the barrel transverse to the axis of said barrel, carriages mounted on said shaft to support the side thrust rollers, said carriages bearing each of them against a supporting roller on one side, abutments on the shaft engaging the supporting rollers on the other side, a rod for transmitting stress received by the side thrust rollers to the frame of the machine, and means on the rod engaging said abutments and said carriages to adjust the side thrust rollers along the shaft and to provide a corresponding adjustment of the supporting rollers in the direction of the length of the shaft.

15. In a sand blast machine, a rotary barrel, a shaft mounted parallel to the axis of said barrel, a supporting roller and an end thrust roller carried by said shaft and engageable respectively with cylindrical and transverse surfaces of said barrel, said end thrust roller being slidably mounted on said shaft.

16. A sand blast barrel machine having a rotary barrel, a frame, rollers on which the barrel is mounted for rotation, side thrust rollers engaging a surface of said barrel transverse to the axis of rotation of the barrel, said latter rollers being adjustable in the direction of the axis of the barrel, stress transmitting means extending in the direction of the axis of the barrel connecting said rollers to the frame of the machine, and means for adjustably fixing said side thrust rollers longitudinally of said stress transmitting means.

Signed by me at Hagerstown, Maryland, this 11th day of February, 1926.

FOSTER J. HULL.
